Primary Examiner — R. Johnson(57) **CLAIM**

The ornamental design for a glove, as shown and described.

DESCRIPTION

FIG. 1 is a front, right side, top perspective view of a glove showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged detailed view of the encircled region 8 shown in FIG. 1.
The broken lines depict portions of the glove that form no part of the claimed design.**1 Claim, 8 Drawing Sheets**(56)
